UNITED STATES PATENT OFFICE.

GEORGE C. BECKWITH, OF MINNEAPOLIS, MINNESOTA.

DESIGN FOR A CAKE OF SOAP.

44,396.

Specification for Design.

Patented July 29, 1913.

Application filed March 1, 1913. Serial No. 751,652. Term of patent 14 years.

To all whom it may concern:

Be it known that I, GEORGE C. BECKWITH, a citizen of the United States, residing at Minneapolis, in the county of Hennepin and State of Minnesota, have invented a new, original, and ornamental Design for a Cake of Soap, of which the following is a specification, reference being had to the accompanying drawings, forming part thereof.

Figure 1 is a perspective view of a cake of soap, showing my new design; and Fig. 2 is a side view of the same.

I claim:

The ornamental design for a cake of soap, as shown.

GEORGE C. BECKWITH.

In the presence of—

HARRY D. KILGORE,
